(57) **CLAIM**

The ornamental design for a battery pack belt, as shown and described.

DESCRIPTION

FIG. 1 shows a perspective view of the battery pack belt.

FIG. 2 shows a frontal view of the battery pack belt.

FIG. 3 shows a rear view of the battery pack belt.

FIG. 4 shows a bottom view of the battery pack belt.

FIG. 5 shows a top view of the battery pack belt.

FIG. 6 shows a first end view of the battery pack belt; and, FIG. 7 shows a second end view of the battery pack belt.

The broken lines shown in the drawings represent environmental effects or potential embodiments and do not form any part of the claimed design.
